UNITED STATES PATENT OFFICE.

JAMES B. McGINLEY, OF ALLEGHENY, PENNSYLVANIA, ASSIGNOR TO NATIONAL METAL MOLDING COMPANY, A CORPORATION OF PENNSYLVANIA.

FIXTURE FOR ELECTRIC LAMPS.

No. 851,024.

Specification of Letters Patent.

Patented April 23, 1907.

Application filed February 19, 1906. Serial No. 301,967.

To all whom it may concern:

Be it known that I, JAMES B. McGINLEY, residing at Allegheny, in the county of Allegheny and State of Pennsylvania, a citizen of the United States, have invented or discovered certain new and useful Improvements in Fixtures for Electric Lamps, of which improvements the following is a specification.

10 The invention described herein relates to certain improvements in bases or supports for electric lamps, such bases or supports being especially applicable where a number of lamps are to be connected in multiple arc 15 to the supply-circuit.

The invention is hereinafter more fully described and claimed.

In the accompanying drawings, forming a part of this specification, Figure 1 shows a 20 number of lamps with my improved bases or supports and conduit-sections containing the circuit-wires interposed between the supports. Fig. 2 is a plan view of the bottom or base portion of the fixture. Figs. 3, 4, and 25 5 are sectional views, the planes of section being indicated, respectively, by the lines III III, IV IV, and V V, Fig. 2, the cap or lamp-socket being shown in position on the base.

30 In the practice of my invention I employ a fixture consisting of base and cover or cap portions formed of porcelain or other non-conducting material. The base portion 1 is provided at its ends with recesses 2 for the reception of the ends of the conduit-sections 3, containing the conductors. Grooves or 35 channels 4 for the reception of the conductors 5 are formed in the upper face of the base and extend from the recesses 2 at one end of the base to the corresponding recesses at 40 the opposite end thereof. Metal contact-plates 6 and 7 are secured to the ridge 8 between the grooves or channels by means of screws, one of said plates being so located 45 that one of the pin-terminals 9 of the lamp when secured in its socket will contact therewith, while the other plate 7 is provided, as shown, with a finger 10, which will extend alongside the sleeve contact or terminal 11 50 of the lamp, as hereinafter described. One of the plates, as 6, extends into one of the grooves or channels and the other plate 7 into the other channel into convenient proximity to the conductors, which are connected

to the plates by any convenient means, as 55 the screws 12.

When metallic conduits are employed, it is necessary that they should be grounded, and in order to avoid a separate ground connection for each section, adjacent sections 60 are electrically connected by a metal strip 13, which is arranged in a groove or channel 13^a, formed in the under side of the base, as shown in Figs. 3 and 4. At its ends this strip is electrically connected to the conduit 65 in any suitable manner. As facilitating the attachment of the strip to the conduit the end portions are bent up into notches 14 in the base and then out, so that the ends will bear upon the conduit adjacent to the ends 70 of the base, as shown in Figs. 2, 4, and 5.

The cap or cover 15 is formed with a socket 16, which is provided with suitable means for holding the lamp. As lamps are now generally formed with threaded stems or base portions, it is preferred to internally thread the socket. The inner wall of the socket is grooved longitudinally for the reception of the finger 10 on the contact-plate 7. When free to move, this finger projects in beyond 80 the inner wall of the socket, but is forced back into the groove when the lamp is screwed in and being of resilient material will bear firmly against the sleeve-terminal of the lamp. By this construction the employment of a metal-lined socket for the lamp is 85 avoided. It is preferred that the finger 10 should be formed with projections on its inner face corresponding with the threads on the inner wall of the socket, as shown in Fig. 4. 90

I claim herein as my invention—

1. A fixture for electric lamps having a base formed of insulating material and provided at its ends with recesses for the reception of the ends of conduits and with grooves 95 in its upper face connecting the recesses, in combination with contact-plates projecting into said grooves and provided with means for connecting the conductors to said plates.

2. A fixture for electric lamps having a 100 base formed of insulating material and provided at its ends with recesses for the reception of the ends of conduits and with grooves or channels in its upper face connecting said recesses and having a groove or channel in its 105 under face, in combination with contact-plates projecting into the upper grooves or channels and provided with means for con-

necting the conductors thereto, and a conducting-strip arranged in the under groove and adapted to be connected to the conduits.

3. A fixture for electric lamps having a base formed of insulating material and provided with grooves or channels in its upper face for the reception of conductors, contact-plates secured to the base and projecting into the grooves, one of said plates provided with an outwardly-projecting finger, in combination with a cap or cover of insulating material and provided with a socket having lamp-engaging means formed integral therewith.

4. A fixture for electric lamps having a base formed of insulating material and pro-

vided with grooves or channels in its upper face for the reception of conductors, contact-plates secured to the base and projecting into the grooves, one of said plates provided with an outwardly-projecting finger, in combination with a cap or cover of insulating material and provided with a socket having spiral ribs or threads formed on its inner wall.

In testimony whereof I have hereunto set my hand.

JAMES B. McGINLEY.
